(57) **CLAIM**

The ornamental design for a temperature detecting apparatus for oven, as shown and described.

DESCRIPTION

FIG. 1 is a front/right-side/top perspective view of a temperature detecting apparatus for oven showing our new design;

FIG. 2 is a front-side elevational view thereof;

FIG. 3 is a left-side elevational view thereof;

FIG. 4 is a right-side elevational view thereof; and,

FIG. 5 is a top-side elevational view thereof.

The lines of the present design in FIG. 1, 2 and 5 are abbreviated about 10 centimeters.
